United States Patent Office.

ALFRED FAUVIN JALOUREAU, OF PARIS, FRANCE.

Letters Patent No. 79,126, dated June 23, 1868.

IMPROVEMENT IN MACHINES FOR MANUFACTURING TELEGRAPHIC CABLES.

The Schedule referred to in these Letters Patent and making part of the same.

TO ALL WHOM IT MAY CONCERN:

Be it known that I, ALFRED FAUVIN JALOUREAU, of Paris, in the Empire of France, manufacturer, have invented "certain new and useful Improvements in the Manufacture of Telegraphic Cables, and in the apparatus connected therewith;" and I do hereby declare that the following is a full, clear, and exact description of the same, reference being had to the annexed drawings, making a part of this specification, and to the letters marked thereon; that is to say—

This invention consists;

First, in an improved method of forming telegraphic cables by the application of successive layers of bitumen, separated and maintained by spiral bands of bituminized paper, and consolidated by one or several coverings of bituminized cordage, the whole encased, when necessary, by metal wire, and an outer coating of bitumen.

Second, in the combination of machinery by aid of which the process of manufacture may be executed with facility, certainty, and economy.

The protection and insulation of the conducting-wires comprise the following operations:

First. Coiling of bituminized cord on the wires, and formation of the cable.

Second. Transit of the cables thus prepared through baths of hot bitumen, to form the successive layers, which are separated and maintained by double envelopes of bituminized paper.

Third. Formation of a protective envelope of bituminized cord or twine.

Fourth. Application, according to circumstances, of a covering of metallic wire.

Fifth. Application of an external coating of bitumen, combined with sand.

Plate 1, Figure 1, of the accompanying drawings, is an elevation of the machinery employed for the manufacture of the cable.

Figure 2 is a plan of the same.

Plate 2, Figure 1, is a section through the line 1-2, fig. 1, plate 1.

Figure 2 is a section through the line 3-4, fig. 1, plate 1.

Figure 3 is a section through the line 5-6, fig. 1, plate 1.

Figure 4 is a longitudinal section of the cable, representing the distribution of the successive protective envelopes.

Figure 5 reproduces, in cross-sections, the different stages of formation of the cable, corresponding with the longitudinal section, fig. 4.

Figure 6 is an external view of the cable, with its casing of iron wire, (in blue,) the coating of bitumen being removed.

Figure 7 is a cross-section of the wooden conduits used in subterraneous lines passing through towns.

A is a drum, carrying the conducting-wire or core, which passes from thence through the gorges of two pulleys, B B', by which it is tightly pressed. These pulleys, by which the wire is regularly carried forward, receive their motion from the main shaft P, through an endless screw, M, mounted thereon, and acting on a toothed wheel fixed on the axle of the lower pulley, B. The upper pulley, B', is so arranged as to press the wire. The latter then passes through a hole pierced in the axle of the gear-wheel b; from thence into the guide-support S, near which it is surrounded by two bituminized twines, delivered by the bobbins C C, the latter rotating round the wire received from the wheel b, on which they are mounted. On leaving these bobbins, the twines pass into two small cylindrical guides, r r, fixed on the guides S, which follows the rotation of the wheel b. These two guides are so arranged as to produce the regular coiling of the two twines at a certain degree of inclination.

In passing over the boiler E, which is charged with melted bitumen, (maintained in fusion by steam from the pipe L or otherwise,) the twine-covered wire comes in contact with the cylinder I, which, rotating partly immersed in the melted bitumen, carries over by adherence a pellicle of the latter. The bitumen thus forms on

the cable a layer, the thickness of which is regulated by a metallic cone, p , passing through it, and secured to the side of the vessel E . From thence the cable passes through the hole pierced in the axle of the wheel b^1 , and receives a double envelope of bituminized paper from the revolving bobbins $D D$. The rotation of these bobbins is produced by the wheel b^1 , on which they are mounted.

The bands of bituminized paper delivered by the bobbins $D D$ pass into the openings $f f$, cut in the guide T , set on and revolving with the wheel b^1 . These openings are so arranged as to compel the paper bands to coil over the cable at a certain degree of inclination, so that the axis of the external band exactly coincides with and covers the joint of the band beneath.

The cable, thus provided with its double envelope of bituminized paper, passes into a second bath of melted bitumen, E^1 , where it receives a new coating. It is then again covered with a double envelope of bituminized paper, delivered by the bobbins $D^1 D^1$, similar to those just described. This operation is repeated three, four, or more times, as may be required, by means of the baths $E^2 E^3$, and bobbins $D^2 D^2 D^3 D^3$, so as to form three, four, or more layers of bitumen, separated by an equal number of envelopes of bituminized paper.

The last paper envelope being applied, the cable passes into the support R^1 , provided with the gear b^1 , and with four bobbins, $C' C' C' C'$, exactly similar to those marked C . It there receives a covering of bituminized twine, supplied by the four yarns of the four bobbins C' , the object of this covering being to protect the core of the cable from accidental injury from without. It is then coated with a final layer of bitumen in the vessel E^3 , which layer is sanded in the case F .

The cable thus prepared passes through the gorge-pulleys $N G O X$, the object of which is to stretch and round it regularly, and to press into the bitumen the sand taken up from the case F .

The gorge-pulley G receives its rotation from a toothed wheel mounted on its axle, and acted on by an endless screw, M' , fixed on the shaft P . The pulleys $O X$ revolve with sufficient speed to give a certain amount of polish to the cable, which from thence is wound off on a store-drum. The shaft P imparts motion to all the twine-bobbins, as also to the bitumen-distributing apparatus, through the pinions $c c' c'' c''' c'''$, &c., the intermediate wheels, $d d' d'' d''' d''''$, &c., acting on the wheels $b^1 b^2 b^3 b^4$, &c. The transmission to the bitumen-distributors is effected by flat belts and pulleys, or by gorge-pulleys and cords.

When a protective wire covering is required, it may be applied to the cable by devices similar to those above described, a final coating of bitumen (or even of twine and bitumen, if necessary) being passed over all, to protect the metal from the action of the air or water. In this case, the wire coils should be applied in a contrary direction to that of the twine envelopes beneath.

The machinery above described may be modified by causing the conducting-wires to revolve, the twine and paper bobbins being kept stationary. To this end, the drum A , and the pulleys $N G O X$, should be mounted on platforms, rotated by a driving-shaft, the forward movement of the wires being effected by pulleys, regulated by a stationary screw, mounted on the support of the drum. The advantage of this arrangement lies in the increased facility of controlling the progress of the work, and of changing the bobbins as required, without stopping the machinery.

In the operations above described, either vegetable or mineral bitumens may be employed, the temperature at which they are melted being varied according to the degree of fluidity required. The inner layers should be formed of more supple material than the exterior coatings, the bitumen being in all cases sufficiently pure to insure perfect insulation. If so desired, the twisted cord or twine may be replaced by untwisted yarn, or other suitable textile material. In certain cases, such as town lines, the cable may be enclosed in creosoted or bituminized wooden conduits, as represented in the section, fig. 7, or in metal, earthenware, or bituminized paper tubes.

Having thus described the nature of the said improvements, and the manner of carrying them into effect, I would have it understood that I do not confine myself to the precise details above laid down, as these may obviously be modified according to circumstances, without deviating from the principles or main features of the invention; but

What I claim, and desire to secure by Letters Patent, is—

1. The improved method of forming telegraphic cables by the application of successive layers of bitumen, separated and maintained by spiral bands of bituminized paper, and consolidated by coils of bituminized twine or yarn, the whole protected, when necessary, by an outer covering of metallic wire, substantially as above specified.

2. The improved combination of machinery, by aid of which the manufacture of the said cable may be effected with facility, certainty, and economy, substantially as herein set forth, and shown in the figures of the accompanying drawings.

A. F. JALOUREAU.
